Fig. I.

Dec. 1289

Walter W. Stanard, of Buffalo, N. Y.

Assignee to
Herman S. Jewett and Francis H. Root, of same place.
Letters Patent No. 1289, Dated July 24, 1860.

The schedule referred to in these Letters Patent and making part of the same.

To all whom it may concern;

Be it known that I, Walter W. Stanard, of the City of Buffalo, County of Erie and State of New York, have invented or produced a new and original ornamental design for Cooking Stoves, and I do hereby declare that the following is a full clear and exact description of the same, reference being had to the accompanying photographic drawings and the letters of reference marked thereon, in which-

Fig. I, represents the front plate of the stove,

Fig. II, represents one of the side plates of the stove

Fig. III, represents one of the end plates of the oven, and

Fig. IV, represents one of the side plates of the oven.

In Fig. I, (a, a) are sliding doors the panels of which are surrounded by quarter round and concave mouldings (b) with reversed striae (c) in relief. In the centre of the panel there is a plain circular emboss, (d), with mouldings (e) on either side nearly surrounding it and terminating at the top and bottom in internal em-

bossed scrolls and having adhering leaves and concave denticulations as represented. The doors above the panels are ornamented with intertwining scroll work (f) and leaves (f') The panels of the jamb on either side of the sliding doors are ornamented with shields (g) with adhering leaves (h).

(i) Fig: II, is the door of the fire chamber surrounded by mouldings similar to those surrounding the panels of the sliding doors (Fig: I).

It has a plain circular emboss (j) in the centre of its panel with mouldings (k) on either side and nearly surrounding it and terminating at the top and bottom in quick scrolls and leaves with leaf like ornaments at the sides as represented.

The side plate back of the door is ornamented with embossed scrolls (l) and flutings (m) as represented. The opposite side plate is the same as the one just described with the exception of the door which is a panel of the same size and with the same ornaments as the door. (n) Are the mouldings at the sides of the end plate of the oven Fig: III. o is a concave and quarter round moulding at the top and (h) a half round moulding at the bottom.

(p) Represents the oven door with its upper corners rounded and having a border (r) of concave denticulations with scalloped edges. In the centre of the door panel is an ovate embossed shield (s) with a border of concave scalloped edged denticulations similar to the border (r).

(t, u) Are concave and quarter round mouldings terminating in reversed scrolls (v, w) and forming an ovate ring around the central shield (s) with adhering leaves (x) at the sides and ends. (y) is an ornamental border of embossed scrolls around the ovate ring (t, u). The opposite end of this plate is the same as the one just described the door being made a stationary panel -

The side plate (Fig: IV) has no mouldings at the sides a concave and quarter round moulding at the top and a half round moulding at the bottom the same as the mouldings surrounding the end plate Fig: III. It has also a similar embossed shield in the centre surrounded by a similar border of concave scalloped edged denticulations and a similar encircling ovate ring of concave and quarter round moulding terminating in reversed scrolls with similar leaf like ornaments at the sides and ends, and additional leaf like ornaments (z) at the sides and embossed scrolls (z') at the ends.

The surface of the plate at the ends outside of the ovate ring is ornamented with embossed scrolls (a') and leaves (b') and volutes (c').

The opposite side plate is a fac. simile of the one just described. Having thus described my design for the ornamentation of cooking stoves, what I claim as new and desire to secure by Letters Patent, is the ornamental arrangement of the figures on the plates of cooking stove as herein described and represented in the accompanying drawings.
